ABRADING SHAFT MOUNTING

Harry L. Myers, Toledo, Ohio, assignor to The
American Floor Surfacing Machine Company,
Toledo, Ohio

Application March 19, 1934, Serial No. 716,409

12 Claims.

(Cl. 51—176)

This invention relates to the surfacing industry and has reference to a novel structural assemblage expressly designed to be embodied in a light weight portable sanding machine of the electric motor operated type now well known in the trade as the "American Light Weight Floor Sander". This invention contains subject matter common to my pending application Serial Number 754,872 filed November 26, 1934.

10 By way of introduction and explanation it is to be pointed out that a machine of the aforesaid variety is illustrated in one of my prior patents entitled "Light weight surfacing machine" and identified under No. 1,934,814 of November 14, 1933. The type of machine disclosed in this patent, as well as in the drawings of the accompanying application embodies a portable wheeled supported frame which, among other parts, constitutes a support for an electric motor and a motor driven sanding drum. Although the drum is not detailed in the patent just mentioned it is to be pointed out in actual practice this drum is in the nature of a metal rubber covered cylinder formed with a slot into which the free ends of a strip of sandpaper or abrasive strip are tucked and held between manually regulated adjustable clamping means.

20 Despite efforts to develop a sanding drum which will insure a smooth even finish on the surface, it has been discovered that the presence of the gap produced by the clamping slot is such as to materially alter the efficiency and accomplishment of the desired uniform surface conditioning results. This is caused by the break in the 30 abrading surface and also by reason of the fact that the wood dust accumulates in the "pocket" formed by this gap, sometimes causing jumping of the drum.

35 The purpose of the present invention is to provide a new type sanding drum of a radially expandable and contractible type such as may be incorporated in the marketed type of machine without requiring extensive alterations or changes in factory equipment, etc. The use of a 40 radial expandable and contractible rubber covered drum or cylinder serves to enable it to accommodate a newly developed endless abrading sleeve which is slipped over the drum and securely held thereon, whereby to promote greater efficiency 45 and more satisfactory abrading and finishing results.

50 In addition to the particular construction of the drum itself, the novelty, as will hereinafter be described, is predicated upon certain refinements and structural distinctions embodied in the

frame construction, especially the bearing means for the shaft which carries the abrading drum.

As will be reflected from the succeeding description structural novelty is predicated upon the quick change abradant drum idea together with the particular frame construction, especially wherein the drum supporting shaft has a rigid bearing on one side and self-adjusting and compensating bearing on the other side associated with a swingable part of the frame which permits 10 access to be had to one end of the drum for exchanging the abrading sleeve.

Other structural distinctions and details upon which added novelty is based will become more explicitly apparent from the following description and drawings.

In the accompanying drawings wherein like numerals are employed to designate like parts throughout the same:

Figure 1 is a side elevational view of the afore- 20 mentioned light weight rotary drum floor sanding machine perfected in accordance with the principles of the present invention.

Figure 2 is a top plan view of the frontal portion of the frame structure, with certain parts 25 removed for clearness of illustration of the main features of the invention.

Figure 3 is a sectional view taken on the plane of the irregular line 3—3 of Figure 1.

Figure 4 is a section on the line 4—4 of Figure 2.

Figure 5 is a sectional view showing the swingable section of the side flange or so-called cover plate swung out to open position.

Figure 6 is a view in section and elevation of 35 the rubber cylinder which constitutes the covering for the improved drum.

Figure 7 is an enlarged fragmentary elevational view detailing the retaining catch or latch feature.

Figure 8 is a perspective view of the keeper or wear plate for the latch.

Figure 9 is a sectional view of the adjustable housing for the self-adjusting or compensating bearing.

Figure 10 is an elevational view of Figure 9 observing it in a direction from right to left.

Figure 11 is an enlarged detail section on the line 11—11 of Figure 4.

Figure 12 is a detail view showing the left hand 50 end portion of the drum structure illustrated in Figure 3 and showing the spring in the bearing housing expanding and shoving said housing to the left.

Figure 13 is a detail perspective view of the 55

type of sanding or abrading sleeve utilized on the new drum.

Referring now to Figure 1 of the drawings it will be seen that the one-piece aluminum frame 5 of the typical or conventional light weight sanding machine previously mentioned (Patent No. 1,934,814) is denoted by the numeral 15, this being provided with a swivelling caster 16 at the rear, steering handle 17, electric motor 18, drum 10 raising and lowering wheel 19, a belt drive 20 from the motor to the power receiving pulley 21 (see Figure 2) on the fixed end of the sanding or abrading drum 22. Other parts of the machine are shown but are of no consequence so 15 far as the novelty of this invention is concerned. Therefore they will not be described. The remaining description will be confined to the construction of the drum and its mounting. As shown in Figure 1 the frontal portion of one side 20 flange of the frame is formed into what may be designated as a swingable bearing stabilizing and drum cover plate 23, this being hingedly mounted to swing outwardly as indicated at 24. As shown in Figure 5 this plate is provided with an aperture 25 in which is fitted an adapter ring 26 of a beveled type to accommodate the correspondingly beveled bearing housing or cup 27. This cup is slidably mounted on a bushing 28 (see Figure 12) through the instrumentality of 30 a retaining washer 30, said bushing being carried by the rotary drum shaft 29. This housing 27 is adapted to accommodate a ball bearing assembly unit 31 permanently attached to one end of the shaft 29, wherein the bearing assembly 35 serves as a stop to limit the outward sliding movement of the housing 27 in a direction from right to left, and wherein the flange on the bushing 28 limits the sliding movement in the opposite direction. The opposite end of the shaft 29 is mounted in a suitable rigid or permanent bearing 32 carried by the depending side flange 33 as shown in Figure 3. Thus, it will be seen that the drum carrying shaft is rigidly supported in a bearing at one end and provided with a belt driven pulley and that the opposite end is equipped with a sliding cup-like housing for the permanently attached bearing assembly 31, this housing being adapted for compensating and adjustable reception in an adapter ring 26 carried by the hingedly 45 mounted cover plate 23. For the purpose of insuring proper association of these parts it will be observed that a coil spring 34 is arranged in the housing as shown in Figures 3 and 12. Thus when the plate 23 is swung outwardly as shown 50 in Figure 5 spring 34 expands and shoves the bearing housing to the left. When the plate is closed the bearing housing is moved in the opposite direction and the spring is compressed to insure tight fitting of the housing in the adapter ring 26. This provides the requisite double bearing support for the shaft 29.

To add to the dependability and efficiency of this arrangement it is necessary to provide means for keeping the plate 23 effectively closed, that is, 55 against swinging outwardly from the frame. This means is described as a latch or catch arrangement and is illustrated in Figures 3 and 11 in particular. Directing attention to Figure 11 it will be observed that the plate 23 is provided 60 with a depression 35 having an opening 36 to accommodate the latch 37. This latch is adapted to releasably engage a wear or keeper plate 38 mounted in the depression, the latch being carried by a swingable arm or mounting 39 pivoted 65 between its ends on a pin 40 carried by a hanger

bracket 41 depending from the under side of the top of the frame as shown in Figure 3. The free or inner end of the arm 42 is provided with a set screw 43 engageable with a stop device 44 also carried by the frame. There is a spring 45 included in this arrangement which presses against the latch carrying arm and forces the latch against its keeper plate. The idea of a pivotal mounting and the set screw is to prevent the latch from swinging, under the action of the 10 spring 45, to a position to make it inaccessible for latching purposes. In other words it is desired to keep the latch in such a position as to allow it to be easily pried open and thereafter to position it so that when the plate is swung closed 15 the latch will automatically snap over the keeper plate 38. It will be noted that the keeper plate is formed with a clearance or tool notch 46 so as to permit a tool to be placed behind the nose of the latch to pry it open. 20

I next call attention to the particular construction of the sanding or abrading drum. As before stated this is of a radially expansible and contractible type and is adapted to accommodate the spirally wrapped or manufactured endless 25 abrading sleeve 60 shown in Figure 13. In order to accomplish this result the type of drum shown particularly in Figure 3 has been found satisfactory.

This drum comprises a relatively fixed conical 30 expander or hub unit 47 and a companion unit 48. The unit 47 is fixedly keyed on the shaft and the unit 48 slidably mounted. A coil spring surrounds the shaft as indicated at 49 and is located between these two units 47 and 48 to press 35 the unit 48 in a direction toward the right when the retaining and clamping nut 50 is released. This nut is mounted on threads 51 formed on the shaft. The nut is provided with sockets to accommodate a spanner wrench (not shown). 40 It will be noticed that the clamping nut is located adjacent the fixed bearing supported end of the shaft, that is adjacent to the fixed flange 33 of the frame. The rubber covering or cylinder shown in Figure 6 is differentiated by the 45 numeral 52 and, it will be observed, has converging conical or beveled surfaces 47a and 48a co-operating with the two converging conical expanders or units 47 and 48 respectively. Thus as these parts are spread apart the inherent 50 : 55 : 60 : 65 : 70 : 75 : 80 : 85 : 90 : 95 : 100 : 105 : 110 : 115 : 120 : 125 : 130 : 135 : 140 : 145 : 150 : 155 : 160 : 165 : 170 : 175 : 180 - It is understood, of course, that the drum, when it is sufficiently small, can be supported solely at one end. In other words the double bearing arrangement is not essential under all conditions.
5. In a large floor sanding machine of the type illustrated the double bearing arrangement is of course essential. It is further understood that the invention is applicable to mandrels as well as to so-called abrading and surfacing drums.
10. Not only this the invention has numerous other commercial features which need not be emphasized in this technical and explanatory description.

Having thus described my invention, what I

15. claim as new is:

1. In a structure of the class described, a frame including a fixed bearing, a shaft mounted for rotation in said bearing, said shaft being provided at the opposite end with a fixedly attached bearing, a slideable spring pressed housing on the last named end of the shaft associated with said last mentioned bearing, said frame including a hinged cover plate having an aperture to accommodate said housing, a beveled adapter ring surrounding said housing, and a sanding drum mounted on said shaft.

2. In a structure of the class described, a frame including a fixed bearing, a shaft mounted for rotation in said bearing, said shaft being provided at the opposite end with a fixedly attached bearing, a slideable spring pressed housing on the last named end of the shaft associated with said last mentioned bearing, said frame including a hinged cover plate having an aperture to accommodate said housing, a beveled adapter ring surrounding said housing, and a sanding drum mounted on said shaft, and a spring pressed manually releasable latch mounted on the frame, said hinged plate being provided with a keeper plate with which said latch is engageable.

3. In a structure of the class described, comprising a wheeled frame carrying a bearing, a single shaft mounted for rotation in said bearing, said shaft being provided at the opposite end with another bearing, a yielding bearing housing associated with the latter bearing, said frame including a movable cover plate having means thereon to support said bearing housing, and a sanding drum mounted on said shaft.

4. In a structure of the class described, comprising a wheeled frame carrying a bearing, a single shaft mounted for rotation in said bearing, said shaft being provided at the opposite end with another bearing, a yielding bearing housing associated with the latter bearing, a removable sanding sleeve carried by the shaft, a movable cover plate carried by the frame, said cover plate permitting the replacement of said sanding sleeve when in one position and constituting a support for the yielding bearing housing when in another position.

5. In a structure of the class described comprising a wheeled frame carrying a bearing, a single shaft mounted for rotation in said bearing, said shaft provided at its opposite end with another bearing, a yielding bearing housing associated with the latter bearing, a yielding sanding drum carried by said shaft, a removable abrading sleeve mounted on the drum, a swinging cover plate mounted on the frame, said plate having a support for said yielding housing, said cover plate permitting replacement of said abrading sleeve when in open position and providing the support for the yielding housing when in the closed position.

6. In a structure of the class described comprising a wheeled frame carrying a bearing, a single shaft mounted for rotation in said bearing, said shaft provided at its opposite end with another bearing, a yielding bearing housing associated with the latter bearing, a yielding sanding drum carried by said shaft, a removable abrading sleeve mounted on the drum, a swinging cover plate mounted on the frame, said plate having a support for said yielding housing, said cover plate permitting replacement of said abrading sleeve when in open position and providing the support for the yielding housing when in closed position, and a latching mechanism carried by the frame and the swinging cover to secure the latter in closed position.

7. In a structure of the class described comprising a wheeled frame, said frame including a top wall and side flanges adapted for shielding a substantial portion of a floor surfacing member, a bearing fixed in one of the side flanges, a single shaft rotatably mounted at one end in said bearing, said shaft carrying a bearing at the other end thereof, a yielding bearing housing associated with the last mentioned bearing, a removable floor surfacing member carried by the shaft, a certain area of the other of said side flanges formed with a movable section, said movable section carrying a support engageable with the yielding housing when in one position and allowing the floor surfacing member to be removed when in another position.

8. In a structure of the class described comprising a wheeled frame, said frame including a top wall and side flanges adapted for shielding a substantial portion of the floor surfacing member, a bearing fixed in one of the side flanges, a single shaft rotatably mounted at one end in said bearing, said shaft carrying a bearing at the other end thereof, a yielding bearing housing associated with the last mentioned bearing, a removable floor surfacing member carried by the shaft, a certain area of the other of said side flanges formed with a hinged section, said hinged section carrying a support engageable with the yielding housing when in the closed position and allowing the floor surfacing member to be removed when in the open position.

9. In a structure of the class described comprising a wheeled frame, said frame including a top wall and side flanges adapted for shielding a substantial portion of the floor surfacing member, a bearing fixed in one of the side flanges, a single shaft rotatably mounted at one end in said bearing, said shaft carrying a bearing at the other end thereof, a yielding bearing housing associated with the last mentioned bearing, a removable floor surfacing member carried by the shaft, a certain area of the other of said side flanges formed with a hinged section, said hinged section carrying a support engageable with the yielding housing when in the closed position and allowing the floor surfacing member to be removed when in the open position, a latch carried by the frame, and means on the hinged section cooperating with the latch for releasably locking the hinged section in closed position for supporting the yielding bearing housing.

10. As a component part of a structural assembly of the class described, an abrading drum including a shaft provided at one end with a relatively fixed bearing and an associated bushing, a tapered cup-like bearing holder slidably mounted on said bearing and including a sepa-

able retention washer slidable on said bushing and movable toward and from said bearing, and a compressed coiled thrust spring contained in said cup-like holder and bearing at one end 5 against said bearing, in the manner and for the purposes described.

11. In a structural assemblage of the class described, a portable frame including an abrading drum and a pivotally mounted member swingable toward and from one end of the drum, said one end of the drum being provided with a shaft, and said member being provided with an adapter opening registerable with said shaft, a bearing associated with said shaft, and a spring-pressed 10 holder and support for the bearing slidably 15

mounted on the bearing to render it projectable and retractable, said holder being slidably receivable in said adapter opening.

12. In a machine of the class described, a frame and abrading drum mounted for rotation 5 in said frame, said drum having a shaft at one end and relatively fixed bearing means mounted on said shaft, that portion of the frame opposed to said bearing means being provided with a shaft accommodation aperture having an adapter 10 ring, and a bearing accommodation and supporting unit of a spring-pressed extensible and retractable type slidably mounted on said bearing and slidably disposed in said adapter ring.

HARRY L. MYERS. 15
